UNITED STATES PATENT OFFICE.

RUSSELL S. MARTIN, OF BINGHAMTON, NEW YORK.

EXTENSION HANDLE FOR CONTROL LEVERS.

Application filed April 24, 1926. Serial No. 104,417.

This invention relates to extension handles for control levers and more particularly to an extension handle for the emergency brake levers of automobiles.

An important object of the invention is to provide a device of this character which may be very readily shifted to positions wherein it does not in any way interfere with movements of the occupants of the vehicle and which, at the same time, may be disposed so that it may be readily grasped by the operator of the vehicle to cause an application of the brake.

A further and more specific object of the invention is to provide a device of this character, particularly adapted for those vehicles of the coach type having a folding seat which necessitates arrangement of the emergency brake handle at a position in advance 20 of the usual position and accordingly at a point where it is substantially inaccessible in order that the shiftable seat of such vehicles may be placed in its folded position to enable the passage of occupants of the vehicle. It will be obvious that a handle of this character must be capable of being positioned so that it will not interfere with the folding of the seat and a further object 25 of the invention is the provision of a handle so constructed.

These and other objects I attain by the construction shown in the accompanying drawing, wherein for the purpose of illustration is shown a preferred embodiment of 30 my invention and wherein:—

Figure 1 is a side elevation partially in section of an extension handle constructed in accordance with my invention showing the same applied to a lever;

Figure 2 is a rear elevation thereof;

Fig. 3 is a section on the line 3—3 of Figure 1;

Figure 4 is a section on the line 4—4 of Figure 1;

Figure 5 is a section on the line 5—5 of Figure 1.

Referring now more particularly to the drawings, the numeral 10 generally indicates a pivoted brake lever having associated therewith a latch 11 coacting with the segment 12 to maintain the brake lever in adjusted positions. These latches are provided with links 13 which, in the usual construction of the lever, are connected with a latch lever (not shown) which is, in turn, pivot-

ally connected, as at 14, to a flattened portion 15 provided upon the upper end of the lever.

In accordance with my invention, I provide a lever consisting of a pair of arms 16 adapted to flatly engage opposite sides of the flattened portion 11 of the lever 10 and combining at their outer ends to produce a solid handle portion 17, the terminal of which is downturned, as indicated at 18, and provides the actual hand grip. The arms 16 are provided with pairs of aligned openings 19 spaced longitudinally of the arms, one of the pairs being employed for the reception of a pivot bolt connecting the arms of the lever 10 at 14. In a second selected pair of openings 19 a second bolt 20 is directed adapted to pivotally receive the eye 21 at the upper end of an extension 22 of one flange 23 of a channel member 24. Intermediate the ends, the flanges of this channel member are provided with aligned openings for the passage of a pin 25 adapted to be received in a notch 26 formed in the convex face of a bowed spring 27, the end portions 28 of which oppose the bight of the channel member and retained there against the pull rod 13 of the latch 11. This spring prevents rattling of the pull rod as well as serving to maintain the pull rod in proper position.

The enlarged upper end 29 of the pull rod, as the handle 18 is elevated, will come into engagement with the upper ends of the flanges of the channel 24 and thereafter will move with the flanges with the result 90 that the latch 11 is elevated and the lever 10 freed for movement. This may be caused through the handle 18. It will be obvious that the handle 18, since it extends considerably rearwardly of the lever 10 will 95 be much more readily accessible to the operator of the vehicle than this lever and accordingly will permit the emergency brake lever to be applied with much less exertion and less of time. It will also be obvious 100 that because of the sliding connection provided between the pull rod 13 and the handle 18, this handle may be folded downwardly so that the arms 16 will lie substantially parallel to the lever 10. In order to permit 105 a maximum movement of this other handle, the handle is slightly offset, as indicated at 30, to permit it to pass to that side of the lever 10 next adjacent the driver of the vehicle. When in this folded position, the 110

extension handle will in no way interfere with folding of the movable seats of coach type vehicles.

It will be noted that by the use of a plurality of pairs of openings 19, the lever may be readily adapted for use in combination with the emergency brake levers of different makes or types of vehicles.

Since the construction hereinbefore set forth is capable of a certain range of change and modification without materially departing from the spirit of the invention, I do not limit myself to such specific structure except as hereinafter claimed.

15 I claim:—

1. In combination with a lever, a latch associated with the lever for retaining the lever in adjusted positions and a pull rod for said latch, a handle pivoted to the lever 20 and extending outwardly at substantially right angles thereto, the outer end of the handle providing a hand grip, a member pivoted to the handle and slidably embracing said pull rod, the upper end of the pull 25 rod having a stop engaging with said member when the handle is elevated to a predetermined degree.

2. In combination with a lever, a latch associated with the lever for retaining the lever in adjusted positions and a pull rod for said latch, a handle pivoted to the lever and extending outwardly at substantially right angles thereto, the outer end of the handle providing a hand grip, a member 35 pivoted to the handle and slidably embracing said pull rod, the upper end of the pull rod having a stop engaging with said member when the handle is elevated to a predetermined degree, said member having in 40 its lower end a channel receiving the pull rod and a spring carried by the member and abutting the pull rod to maintain the

same in engagement with the inner wall of the bight of the channel.

3. In combination with a lever, a latch 45 associated with the lever for retaining the lever in adjusted positions and a pull rod for said latch, a handle pivoted to the lever and extending outwardly at substantially right angles thereto, the outer end of the handle providing a hand grip, a member pivoted to the handle and slidably embracing said pull rod, the upper end of the pull 50 rod having a stop engaging with said member when the handle is elevated to a predetermined degree, said handle being transversely offset to thereby permit the hand grip to move past the lever so that said handle may approximately parallel the 55 lever.

4. In combination with a lever, a latch associated with the lever for retaining the lever in adjusted positions and a pull rod for said latch, a handle pivoted to the lever and extending outwardly at substantially right angles thereto, the outer end of the handle providing a hand grip, a member pivoted to the handle and slidably embracing said pull rod, the upper end of the pull 60 rod having a stop engaging with said member when the handle is elevated to a predetermined degree, said member having in its lower end a channel receiving the pull rod, a pin connecting the side walls of the channel and a bowed spring having in its 65 bight portion a notch for engagement with said pin and having the ends thereof engaging said pull rod to maintain the same in engagement with the bight of the channel.

In testimony whereof I hereunto affix my signature.

RUSSELL S. MARTIN.
